(57) **CLAIM**

An ornamental design for a lounge chair towel, as shown and described.

DESCRIPTION

FIG. 1 is a perspective view of the lounge chair towel, showing my new design;

FIG. 2 is a right-side view thereof;

FIG. 3 is a left-side view thereof;

FIG. 4 is a top view thereof;

FIG. 5 is a bottom view thereof;

FIG. 6 is a front view thereof; and,

FIG. 7 is a rear view thereof.

The broken lines depict portions of the article that form no part of the claimed design. Areas depicted in cross hatch represent a mesh pouch.
